Attorney.

UNITED STATES PATENT OFFICE

2,386,479

TOY GUN

Charles H. Kuhn, Indianapolis, Ind.

Application March 16, 1944, Serial No. 526,664

1 Claim. (Cl. 46—189)

This invention relates to a toy gun of the noise making type, and it has for a primary object cheapness and simplicity of structure whereby the gun may be produced and sold at a minimum cost with the use of a minimum amount of material. A further primary object of the invention is to provide such a structure in a form whereby moving parts are reduced to a simple bendable element mounted simply by insertion within a sounding well all without the use of securing elements such as rivets, screws, bolts, etc.

These and many other objects and advantages of the invention will become apparent to those versed in the art in the following description of one particular form of the invention, as illustrated in the accompanying drawing, in which

Fig. 1 is a view in side elevation and partial section of a structure embodying the invention;

Fig. 2 a view of the structure in bottom plan view; and

Fig. 3 a view in plan elevation of the trigger and sound producing element.

Like characters of reference indicate like parts in the several views of the drawing.

The gun proper herein shown as representing a revolver, is generally designated by the numeral 10. It is preferably made out of wood so that it may be readily cut out of a board by any suitable means, such as, sawing to give the desired shape. The cylinder is represented by a pair of rounded blocks 11 and 12 glued or otherwise secured to the sides of the board member.

Immediately forward of the handle or stock 12 is drilled a circular hole 13 from the underside of the board member to have the bore thus produced extend well up into the wood as indicated in Fig. 1. A length 14 of flat spring steel is cut to that length which will have an extension thereof below the underside of the gun when that length 14 is inserted in the bore 13 toward its upper end. The width of the steel member 14 is made to be about five eighths inch and the bore 13 one half inch so that the steel member will have to be forced into the bore in a diametrical plane thereof to have the member 14 frictionally retained therewithin. Preferably the edges of the member 14 are provided with barbs 15 which will engage in the wood wall of the

bore 13 to resist withdrawal of the member 14 therefrom. It is not necessary to have the inner end of the steel 14 seat against the inner end of the bore 13, whereby precise dimensions as to length need not be maintained.

The member 14 is further provided with a circular buckle 16 centrally of its width and is substantially centered longitudinally of the member 14 in the plane of the underside of the gun 10.

10 The end of the member 14 which projects from the bore 13 is positioned to be convenient for the index finger of the operator to extend therearound and serve as a trigger when the butt or handle 12 of the gun 10 is gripped. By pulling 15 the projecting end of the member 14 toward the handle 12, the buckle 16 is distorted so that when the member 14 is released, there will be a "pop" noise which is accentuated by reverberations in the well or bore 13. This action, of course, may 20 be repeated as quickly as the member 14 is pulled and released. The buckle in the present instance consists simply of a circular depressed portion of the steel.

While I have herein described and shown my 25 invention in one precise form, it is obvious that structural changes and material substitutions may be made without departing from the spirit of the invention, and I therefore, do not desire to be limited to that precise form beyond the 30 limitations as may be imposed by the following claim.

I claim:

A toy gun in the nature of a pistol comprising 35 a barrel-like portion; a handle with a down-turned portion from which an upper portion merges into the barrel portion from its underside to give a vertically thickened barrel portion section thereby; said thickened portion having a vertical cylindrical bore therein in front of 40 said downturned handle portion and closed at its upper end and open at its lower end; and a buckled flat steel spring leaf embedded and frictionally retained by its side edge portions in diametrically opposed wall portions of said bore with 45 a length of said leaf extending from the bore as a bendable trigger in front of said handle downturned portion.

CHARLES H. KUHN.
